ABSTRACT OF THE DISCLOSURE

A track is tamped in a regular succession of repeating tamping operations as the track tamper advances along the track. A group of at least two ties is tamped in each of the operations, each of which is identical with the preceding one.

This is a continuation of our copending application Ser. No. 536,380, filed Mar. 22, 1966, now abandoned, and a continuation-in-part of applications Ser. No. 495,123, filed Oct. 12, 1966, now Patent No. 3,380,395, and Ser. No. 497,288, filed Oct. 18, 1965, now abandoned.

The present invention relates to railroad track maintenance, and more particularly to improvements in ballast tamping.

Mobile track tampers with or without means for aligning and/or grading the track are known. In our application Ser. No. 441,229, filed Mar. 19, 1965 now Patent No. 3,372,651, we have disclosed a machine of this type with a plurality of tamping tool assemblies. Such tamping tool assemblies may be individually movably mounted on the machine so that their position may be adjusted in the direction of the track elongation and in respect of the track ties to be tamped. Preferably, as disclosed in our application Ser. No. 495,123, the tamping tool assemblies are mounted for movement on the tamper in the direction of elongation of the track, and means is provided for coupling the assemblies in a group of at least two assemblies for simultaneous movement of the group of assemblies in said direction. Also, as disclosed in our application Ser. No. 497,288, means for laterally aligning the track are preferably mounted intermediate the front and rear axles of the mobile machine.

The term "tamping tool assembly" designates ballast tamping means designed to tamp the ballast underneath a tie. In the well known assembly illustrated herein by way of example, each tamping tool assembly includes a pair of tools spaced from each other in the direction of elongation of the track, and opposing tools of each pair being arranged for immersion in the ballast adjacent a selected tie and for reciprocation in the direction of the track elongation, such as disclosed, for instance, in our U.S. Patents Nos. 2,876,709 and 2,915,018.

It is the principal object of this invention to improve the efficiency of track tamping.

This object is accomplished by tamping track ties along a track section in a succession of like tamping operations, wherein each operation includes the simultaneous tamping of a group of at least two ties.

In one specific embodiment, each group includes two ties, a first one of the groups of ties encloses two ties that have not been previously tamped, a first one of the untamped ties is skipped in a subsequent tamping operation, and a second one of the untamped ties is tamped as a tie of the group in the subsequent tamping operation. One tie is skipped between all successive tamping operations.

2

In another specific embodiment, each group includes, in the direction of advance of the succession of tamping operations, a hindmost tie, an intermediate tie and a foremost tie. The hindmost and intermediate ties of a first group of ties encloses a first set of previously untamped ties, and the intermediate and foremost ties of the first group enclose a second set of previously untamped ties. The two hindmost untamped ties in the first set are skipped in a subsequent tamping operation, and the foremost untamped tie in the first set is tamped as a tie of the group in the subsequent operation. Two ties are skipped between all successive tamping operations.

Other objects, advantages and features of the present invention will become apparent in the following detailed description of certain preferred embodiments thereof, taken in conjunction with the accompanying drawings wherein:

FIG. 1 schematically shows one embodiment of the tamping method of this invention; and

FIG. 2 similarly illustrates another embodiment thereof.

Since track tampers useful in the method of the present invention are generally well known and specific tampers useful in carrying out this method have been particularly disclosed and claimed in our above-identified copending applications, and since the present invention is not concerned with any specific apparatus, a useful mobile tamper for carrying out one embodiment of this invention has been merely schematically shown in FIG. 1, to include a machine frame 1 supported on front and rear axles 2 and 3 for movement on a track consisting of rails 4 resting on ties 5, the direction of advance of the mobile track tamper during the tamping being indicated by an arrow. The machine frame carries two tamping tool assemblies 6' and 7'. Since not directly pertinent to the present invention, neither the operating or moving means, if any, for the tamping tool assemblies nor the track aligning and/or grading means conventionally mounted on the machine frame are shown.

In the method of FIG. 1, each tamping operation includes the simultaneous tamping of two ties, and seven successive like tamping operations are shown. The first group of ties A₁ and A₂ encloses two ties that have not been previously tamped. After the first tamping operation is completed, the tamper is advanced in the direction of the arrow along the track section sufficiently to skip a first one of the untamped ties. With the tamping tool assembly 6' aligned with the second one of the untamped ties, the group of ties B₁ and B₂ is tamped in the subsequent like tamping operation. Next, one tie is skipped again to tamp the group of ties C₁ and C₂, this being successively continued with a like skipping of one tie and tamping of successive groups D₁—D₂, E₁—E₂, F₁—F₂ and G₁—G₂ (not shown) in the illustrated manner. Thus, in each of the successive tamping operations, one of the untamped ties between two previously tamped ties is tamped, adjacent ties being tamped one after the other as the tamper advanced along the track, all ties between ties B₁ and F₂ having been tamped at the end of a succession of like tamping operations. As is obvious from the drawing, the distance between the two tamping tool assemblies 6', 7' remains unchanged in the successive tamping operations.

More than the two tamping tool assemblies may be mounted on the machine frame, the number of assemblies being limited only by the acceptable length of the machine frame. FIG. 2 illustrates an embodiment wherein in three tamping tool assemblies 6, 7 and 8 are mounted on the machine frame 1 for tamping in groups of three ties. Again, seven successive like tamping operations are shown, a hindmost, an intermediate and a foremost tie, in the direction of advance of the tamper, being simultaneously tamped in each successive operation. As shown

on top of FIG. 2, the hindmost and intermediate ties of the first group encloses a first set of previously untamped ties, and the intermediate and foremost ties of the first group encloses a second set of previously untamped ties. In the subsequent tamping operation I, the two hindmost untamped ties in the first set adjacent the tamped tie A_1 are skipped, and the foremost untamped tie B_1 in the first set adjacent tamped tie A_2 is tamped as a tie of the group including ties B_2 and B_3 . In the next successive operation II, two ties are skipped again to tamp the group of ties $C_1-C_2-C_3$, the same procedure being repeated in successive operations III, IV, V and VI to tamp the groups of ties $D_1-D_2-D_3$, $E_1-E_2-E_3$, $F_1-F_2-F_3$ and $G_1-G_2-G_3$ (the latter tie not being shown.) After the tamping operation following operation VI (not shown), 15 all ties between tie C_1 and F_3 will have been tamped.

It will be obvious from the above description of specific embodiments and variations of the tamping method of the present invention that its essential feature is the successive tamping of groups of n ties in like tamping 20 operations along a track section to be aligned and/or graded. In such operations, as is well known, the position of the track section is first corrected, the corrected track section is held in the corrected position and, while so held, the ties in the corrected track section are tamped to fix the track section in the corrected position.

Each pair of a group of ties being tamped simultaneously encloses two or more ties which are tamped in subsequent groups while the tamper advances along the track section, skipping one or more ties from one operation to the other, as shown in FIGS. 1 and 2. This makes a continuous operation possible without changing the spacing of the tamping tool assemblies in relation to each other (unless the spacing of the ties varies). Therefore, the tamping tool assemblies may be immersed into the ballast 35 promptly at each intermittent stop of the tamper to start tamping without any loss of time.

While the invention has been described in connection with certain specific embodiments, it will be clearly understood that many variations and modifications may occur to those skilled in the art, particularly after benefiting from the present teaching, without departing from the spirit and scope of this invention.

What we claim is:

1. A method of tamping ties along a track section with a mobile track tamper carrying a number n of tamping tool assemblies spaced in the direction of elongation of the track section in alignment with a group of n ties, comprising the steps of

- (a) simultaneously tamping a group of n ties in a tamping operation, said group of n ties enclosing an equal number previously tamped and of untamped ties;
- (b) subsequently advancing the track tamper by successive distances of n ties until the tamping tool assemblies are in successive alignment with successive groups of n ties; and
- (c) simultaneously tamping each successive group of n ties in successive tamping operations.

2. The method of claim 1, wherein $n=2$.

3. The method of claim 2, wherein a first one of said enclosed ties is skipped in each succeeding tamping operation while a second one of said enclosed ties is the one tie tamped in each preceding tamping operation.

4. The method of claim 1, wherein $n=3$.

5. The method of claim 4, wherein said groups of three ties include, in the direction of advance of said track tamper, a hindmost tie, an intermediate tie and a foremost tie, the hindmost and intermediate ties of the group tamped during each successive tamping operation enclosing one previously untamped tie and two previously tamped ties, and the intermediate and the foremost ties of said group enclosing two previously untamped ties and one previously tamped tie.
